UNITED STATES PATENT OFFICE

RICHARD C. COUPLAND, OF NORFOLK, VIRGINIA

AMMUNITION-FEED BOX

Application filed November 7, 1929. Serial No. 405,466.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

5 The subject of this invention is an ammunition feed box especially applicable for machine guns mounted on aircraft or land vehicles where space is extremely limited and the gunner is obliged to position the box and load 10 the gun with one hand.

In providing ammunition feed boxes with cartridge feeding apparatus the trend of development has been toward complicated structure and involved mechanisms. The 15 box is, therefore, an expensive unit and instead of being thrown away when empty, it is retained for the purpose of recharging.

The purpose of this invention is to provide 20 a cartridge feeding device in a light, waterproof container which will serve both as a shipping carton and as a magazine and will be so inexpensive that it may be discarded after a single use.

25 The cartridge feeding device is associated in a novel manner with the cover of a container and is arranged to be capable of securely holding the cartridge belt in loading position in the feedway of the gun when the cover of the gun is raised for the purpose of correcting stoppages.

30 With the foregoing and other objects in view, the invention resides in the novel arrangement and combination of parts and in the details of construction hereinafter described and claimed, it being understood that changes in the precise embodiment of the invention herein disclosed may be made within the scope of what is claimed without departing from the spirit of the invention.

40 A practical embodiment of the invention is illustrated in the accompanying drawings, wherein:

45 Fig. 1 is a view in side elevation of the improved ammunition feed box, parts being broken away to show the normal position of the first round of the ammunition belt;

Fig. 2 is a plan view;

50 Fig. 3 is a view in side elevation showing the belt advanced into the feedway of a machine gun;

Fig. 4 is a plan view of the same;

Fig. 5 is a fragmentary view in rear elevation of the upper portion of the feed box;

Fig. 6 is a detail sectional view of a portion of the cover.

Referring to the drawings by numerals of reference:

The ammunition feed box 4 is in the form of a rectangular open carton of light metal or waterproof fiber-board adapted to contain a belt 5 of ammunition. The front wall 6 which is adjacent the gun 7 when the box is placed in the support 8 is terminated short of the top of the box to form an exit 9, the dimensions of which are substantially equal to a cartridge 10. The upper edge of the front wall is bent outwardly to provide a lip 11 which when the box is in position is level with and extends practically to the floor 12 of the feedway 13 of the gun to insure a smooth movement of the cartridges. The lip is of sufficient width to support the first round of the belt in such a position that when the box is lowered into the support 8 the round will not strike the cover 14 of the gun.

The cover 15 of the feed box is conveniently mounted for sliding movement by means of a tongue and groove connection, in the present instance the tongue 16 being provided by flanging the side plates 17 of the container and the groove 18 being formed by turning over or channeling the sides of the cover. The cover is of less length than the opening of the feed box and the near 80 or front side is provided centrally with a recess 19 (Fig. 2). A leaf spring 20 serving in the capacity of a belt advancing pawl is secured externally to the cover and is normally depressed below the plane of the cover within the recessed portion 19. The pawl

85 includes a pair of spaced fingers 21 of varying length to effectively engage the tapered side of the round on each side of the belt 5, which belt may be either of fabric or metallic disintegrating link construction. The fingers 21 exert sufficient pressure to insure retention of the first round in the exit 9 and to prevent accidental withdrawal of the belt.

90 When the cover is in the loading position shown in Figs. 3 and 4, having been moved

to the right, the fingers 21 will be disposed at the sides of the slide carrying the belt feed pawl 22 of the gun and the recess 19 of the cover will permit actuation of the pawl 22 without interference. The cover itself in this position constitutes a deflecting plate guiding the rounds into the exit 9 as they are withdrawn with great rapidity from the box.

10 A spring 23 carried by the cover is selectively engageable in recesses 24-25 in one of the tongues 16 to respectively hold the cover in the normal position and in the loading position. With the cover of the feed box held in the loading position, the cover 15 14 of the gun may be raised for the purpose of gaining access to the bolt to clear stoppages without fear of losing the belt for the reason that the fingers 24 will cooperate 20 with the floor of the feedway and with the feedstop pawl 26 of the gun to securely hold the belt against displacement. When the stoppage is remedied the gun cover may be 25 lowered and the gun loaded by retracting the bolt manually in the usual manner.

The cover of the feed box is normally moved by grasping the sides between the thumb and fingers, but if on occasion sufficient force can not be applied in this manner, the far or rear side of the cover which is turned down to form a skirt 27 may be struck a sharp blow with the palm of the hand.

When using the feed box as a shipping 35 container or when it is in storage, a readily detachable covering may be placed over the exposed or open portion of the top. The operations of placing the feed box in the support 8 and actuating the cover to advance 40 the ammunition belt into the feedway of a gun may be easily and quickly performed with one hand.

The box being of regular pattern and outline may be conveniently stored in the restricted space afforded in the cockpit of an airplane.

I claim:

1. The combination with a machine gun having a feedway for a cartridge belt, of an ammunition box supported adjacent the feedway and adapted to contain a cartridge belt, the upper edge of the front wall of the box turned over to provide an exit positioned to register with the feedway, a cover slidable on the feed box, a feed pawl carried by the cover and normally holding the end round of a cartridge belt in the exit and means for holding the cover in place after it is moved to advance the belt into the feedway of the gun.

2. The combination with a machine gun having a feedway for a cartridge belt, of an ammunition box supported adjacent the feedway and adapted to contain a cartridge belt, an exit in the box positioned to register

with the feedway, a cover slidable on the feed box, a feed pawl carried by the cover and normally holding the end round of a cartridge belt in the exit and means for holding the cover in place after it is moved to advance the belt into the feedway of the gun.

3. An ammunition feed box comprising a container, the upper portion of the front wall being turned over to provide an exit dimensioned to pass a cartridge, the upper portion of the side walls being turned over to provide a tongue, a cover having turned over portions fitting over the tongues, said cover being of less length than the feed box and having a recess centrally in its front side, a feed pawl secured externally to the cover and including spaced cartridge engaging fingers depressed into the recess and extending to the exit in the front wall of the container to normally hold a cartridge in the exit, and means for holding the cover in place after it is moved to advance the cartridge out of the exit.

4. An ammunition feed box comprising a container, the upper portion of the front wall being turned over to provide an exit dimensioned to pass a cartridge, a cover slidable on the container, said cover being of less length than the feed box and having a recess centrally in its front side, a feed pawl secured externally to the cover and including spaced cartridge engaging fingers depressed into the recess and extending to the exit in the front wall of the container to normally hold a cartridge in the exit, and means for holding the cover in place after it is moved to advance the cartridge out of the exit.

5. An ammunition feed box comprising a container, the upper portion of the front wall being turned over to provide an exit dimensioned to pass a cartridge, a cover slidable on the container, said cover being of less length than the feed box and having a recess centrally in its front side, a feed pawl secured externally to the cover depressed into the recess and extending to the exit in the front wall of the container to normally hold a cartridge in the exit, and means for holding the cover in place after it is moved to advance the cartridge out of the exit.

6. An ammunition feed box comprising a container, the upper portion of the front wall being turned over to provide an exit dimensioned to pass a cartridge, a cover slidable on the container, said cover being of less length than the feed box, a feed pawl secured to the cover and extending to the exit in the front wall of the container to normally hold a cartridge in the exit, and means for holding the cover in place after it is moved to advance the cartridge out of the exit.

7. An ammunition feed box comprising a container having a cartridge exit at the upper end of its front wall, a cover slidable on the container and terminating short of the front

wall thereof, spaced cartridge engaging feed pawls secured to the cover and extending to the exit of the container, means for holding the cover in place before and after it is moved

5 to advance the feed pawls beyond the exit.

8. An ammunition feed box comprising a container having a cartridge exit at the upper end of its front wall, a cover slidable on the container and terminating short of the front wall thereof, spaced cartridge engaging feed pawls secured to the cover and extending to the exit of the container, means for holding the cover in place after it is moved to advance the feed pawls beyond the exit.

10 15 9. An ammunition feed box comprising a container having a cartridge exit at the upper end of its front wall, a cover slidable on the container and terminating short of the front wall thereof, a cartridge engaging feed pawl secured to the cover and extending to the exit of the container, and means for holding the cover in place after it is moved to advance the feed pawl beyond the exit.

20 25 10. An ammunition feed box comprising a container having a cartridge exit, a cover slidable on the container, a feed pawl carried by the cover and normally extending into the exit and means for holding the cover in place after it is moved to advance the feed

30 35 11. An ammunition feed box comprising a container having a cartridge exit, a cover slidable on the container, and a feed pawl carried by the cover and normally extending into the exit.

40 12. An ammunition feed box comprising a container having a cartridge exit, and a cover slidable on the container and having cartridge engaging means for advancing a cartridge through the exit.
